UNITED STATES PATENT OFFICE

J. H. BLOOMFIELD, OF CHICAGO, ILLINOIS.

IMPROVED FURNITURE-CASTER.

Specification forming part of Letters Patent No. 36,890, dated November 11, 1862.

To all whom it may concern:

Be it known that I, J. H. BLOOMFIELD, of the city of Chicago, in the county of Cook and State of Illinois, have invented a new and useful Improvement in Furniture-Casters; and I do hereby declare that the following is a full, clear, and exact description thereof, reference being had to the accompanying drawings, and to the letters and figures marked thereon, which form a part of this specification.

In the aforesaid drawings, Figure 1 shows a side elevation of my improved furniture-caster; Fig. 2, a sectional view through the center of the same; Fig. 3, a transverse section of the caster at the line α in Fig. 2; and Fig. 4 represents the flange or rim, which retains the ball B in place, unattached.

Similar letters in the different figures in said drawings represent and denote the corresponding parts of my invention.

To enable others skilled in the art to understand the construction of my improved caster, I will now proceed to describe the same with particularity.

The material of which I construct my improved caster is generally cast-iron; but it may be made of brass or any other suitable metal. The ball marked B, I prefer to make of cast-iron in all cases.

The nature of my invention consists in constructing a caster in such a manner that a ball may be and is used in the place and stead of the common wheel or swivel for that part of the caster upon which the furniture is rolled or moved from one place to another, the caster being at the same time much stronger, more durable, and less liable to get out of repair than the ordinary kind.

In the accompanying drawings, A represents a socket whereby the caster may be attached to the legs or supports of the furniture. C is a cup or socket to contain the ball marked B in the drawings; and D is a circular flange or rim which, for the purpose of retaining and keeping the ball B in place, is attached and fastened to the lower edge of the cup C by means of the screw cut in the outer circumference of the flange and inner circumference of the cup C, as shown in the drawings, or by any other equivalent and suitable method. The internal diameter of the cup C, as may be seen in the drawings, is greater than the diameter of

the ball B, which is kept in the center of the cup by the points or supports a c , upon and within which it freely moves. These supports are the only points of contact between the ball and cup. The entire weight of the furniture, when at rest, falls on the point a , and when in motion the whole of the friction caused by its weight is at the point a and two of the points c , or only one.

The point or support a in the apex of the cup is a projection cast upon it, and not a separate anti-friction piece inserted therein; and the points c , (which receive the lateral pressure of the ball,) lying in the same horizontal plane, are arranged about the interior of the cup at equal distances from each other, so that a straight line drawn from one of said points to the adjacent point will subtend an arc of exactly one hundred and twenty degrees. By the peculiar arrangement of the three points c , in whatsoever direction the caster may be moved, the lateral pressure of the ball cannot come upon more than two points, and when moved in either of three directions—namely, of the lines passing through the center of the ball and either of the said three points—the lateral pressure of the ball can come upon only one of the said points, thus occasioning the least possible amount of friction, which object is effected only when the number of points is three and when these three points are arranged in precisely the manner described. The lower part of the ball B projects below the lower edge of the flange D sufficiently to permit it to roll freely about on the floor.

I do not claim the method of attaching the caster to the furniture by the socket A, nor any particular method; but it may be attached in any suitable manner; but

What I claim as my invention is—

The peculiar arrangement of the three points c , in combination with the point a , when the same are used in combination with the cup and ball of a furniture-caster, all being constructed, arranged, and operating substantially as and for the purposes delineated and set forth.

J. H. BLOOMFIELD.
